UNITED STATES PATENT OFFICE.

WILLIAM H. VAN HORN, OF BALTIMORE, MARYLAND, ASSIGNOR TO CLARENCE M. KEMP, OF BALTIMORE, MARYLAND.

BRAZING-BURNER.

1,033,967.

Specification of Letters Patent. Patented July 30, 1912.

Application filed May 27, 1910. Serial No. 563,773.

To all whom it may concern:

Be it known that I, WILLIAM H. VAN HORN, a citizen of the United States, residing at Baltimore, in the State of Maryland, have invented new and useful Improvements in Brazing-Burners, of which the following is a specification.

This invention relates to blast burners, and has for its object to provide a tool of the type especially adapted for the use of a hydrocarbon gas as a fuel, such as is produced by the intermingling or combination of gasolene and air.

Blast or brazing burners in use at the present time form the jet by burning a mixture of any suitable gas with air or steam fed through separate pipes to the nozzle, where they combine, either the gas or air or steam being under pressure to form the jet of flame necessary for the operation of the tool. With this type of burner hydrocarbon gas cannot be successfully employed as the pressure of the air or steam, or of the gas itself, immediately extinguishes the flame; nor is it possible to preserve the jet of flame when the gasolene gas is used alone under pressure without employing a pilot light burning continuously so long as the tool is in use.

To overcome the difficulties encountered in the use of gasolene gas, the burner hereinafter described in detail has been devised and consists broadly of two independent pipes, each receiving a supply of gasolene gas under pressure from a common source by separate channels provided with pressure reducing means, one of said pipes being fitted with a jet nozzle and the other pipe terminating in a pilot burner adjacent the outlet of said nozzle. If, now, the pilot be lighted and gasolene gas admitted to the jet pipe, the gas, on emerging from the nozzle, is lighted and kept burning by the pilot light, producing a long pencil of flame pointed at the end.

With this object in view, the invention consists of the novel construction and combination of parts hereinafter described and claimed, and illustrated in the accompanying drawing, in which—

Figure 1 is a side view of the improved blast or brazing burner; Fig. 2, a vertical longitudinal sectional view thereof, enlarged; Fig. 3, a view of the nozzle end of the tool; Figs. 4 and 5, cross-sectional views

on the lines 4—4 and 5—5, respectively, of Fig. 2; Fig. 6 is a longitudinal sectional view of a modified form of the blast burner; Fig. 7, a top view of the nozzle end of the modified burner, and Fig. 8, an end view of the same.

In the drawing, the reference numeral 1 designates a pipe for conducting hydrocarbon or gasolene gas to the body 2 of the burner from which project two pipes 3 and 4, the pipe 3 terminating in a jet nozzle 5, and the pipe 4 being fitted with a pilot burner 6. In the body 2 is a chamber 7 to receive gas under pressure from the inlet pipe 1, and two passageways 8 and 9 leading from the chamber, the former opening into the pipe 3 and the latter into the pipe 4. The quantity and pressure of gas passing to the nozzle and pilot is regulated by screw plugs or other appropriate means 10 and 11 in the respective passageways 8 and 9.

In the preferred form of the invention illustrated in Figs. 1 to 5, the pipes 3 and 4 are concentrically arranged, the blast pipe 3 being within the pilot burner pipe 4, whereas in the modified construction, the pipes 3^a and 4^a are placed side by side, either parallel as shown, or in any other desired manner. The nozzle 5, when the pipes 3 and 4 are concentric, projects a short distance beyond the pilot 6, which is provided with a ring of fine holes 12 surrounding said nozzle, through which holes gas at low pressure emerges, and when lighted inclose the nozzle outlet 13 in a flame to keep the jet of gas emerging therefrom under pressure, always lighted. The nozzle and pilot may be integral, or made in two connected parts. To prevent outside currents of air from extinguishing the pilot light, a rim 14 projects beyond the holes 12 and nozzle 5 forming a combustion chamber, and may, if thought advantageous, have a reduced outlet 15.

The pilot burner 6^a in the modification, is made in the form of a hollow box having a perforated concave side 16, to partly embrace the outlet end of the jet nozzle 5^a, and extending both in advance and in rear of said outlet end, the perforations in the rear being desirable to relight the burner, should the jet at any time blow out the light from the openings in front of the nozzle.

A cock 17 is provided in the body 2, or in the jet pipe to admit and cut off gas to the

nozzle, and regulate the jet by the quantity of gas fed thereto.

From the above description, it will be apparent that a simple, convenient and practical blast or brazing burner for using a hydrocarbon gas as fuel, has been devised, and has proven very efficient in actual use.

In operation, the flame of the pilot burner fills the cavity within the rim 14, surrounding the outlet of the jet nozzle and protrudes slightly outside said rim, as shown in Fig. 1. The gas under pressure issuing from the nozzle is forced through the pilot flame and ignited thereby, and kept lighted so long as gas continues to flow from the nozzle.

Having thus described my invention, what I claim and desire to secure by United States Letters Patent is:—

20. 1. In a brazing burner, a body having a fuel chamber, means for conveying hydrocarbon gas under pressure to said fuel chamber, a jet nozzle connected by a passage to said fuel chamber, a pilot burner in proximity to the jet nozzle connected by a separate passage to said fuel chamber, said pilot burner having a plurality of outlets and adapted to maintain the flame of the jet nozzle against extinction by the pressure of the gas, means in each passage for separately regulating the flow of gas to the jet nozzle and the pilot burner and a cut off valve for the jet nozzle.
25. 2. In a brazing burner, a body having a fuel chamber and separate passages leading from said fuel chamber, means for conveying hydrocarbon gas under pressure to said fuel chamber, a jet nozzle, a pipe connected to said jet nozzle and to the body opening into one of said passages, a pilot burner in close proximity to the jet nozzle, a pipe connected to said pilot burner and to the body and communicating with the other passage, said pilot burner having a plurality of outlets and adapted to maintain the flame of the jet nozzle against extinction by the pressure of the gas, an adjustable valve for regulating the quantity and pressure of gas passing through each pipe, and a cut off valve for the jet nozzle forward of the regulating valve therefor.
30. 3. In a brazing burner, a body having a fuel chamber, and two separate passage-ways therein opening into the fuel chamber, an imperforate pipe leading from each passage-way, means for delivering hydrocarbon gas under pressure to said fuel chamber, a jet nozzle on one of said pipes, a pilot

burner on the other pipe adapted to produce a spreading flame in close proximity to the jet nozzle to prevent the flame of the jet nozzle from being extinguished by the pressure of the gas, adjustable regulating valves in the gas passages, and a cut-off valve for the jet nozzle in advance of the adjustable valve therefor.

4. In a brazing burner using hydrocarbon gas under pressure as a fuel, a body having a fuel chamber, means for delivering hydrocarbon gas thereto, a jet nozzle, a pilot burner in close proximity thereto, means for conveying hydrocarbon gas from the fuel chamber to the jet nozzle, separate means for conveying hydrocarbon gas from the fuel chamber to the pilot burner, said pilot burner being adapted to produce a spreading flame to prevent the flame of the jet nozzle from being extinguished by the pressure of the gas, regulating valves for the jet nozzle and the pilot burner, and a cut-off valve for the jet nozzle.

5. In a brazing burner, a body forming a part thereof containing a fuel chamber, means for conveying hydrocarbon gas under pressure to said fuel chamber, a jet nozzle connected to said fuel chamber, a pilot burner in proximity to the jet nozzle connected by a separate passage to said fuel chamber, and separate means for regulating the flow of gas to the jet nozzle and to the pilot from the common fuel chamber, said pilot burner having a plurality of outlets and adapted to maintain the flame of the jet nozzle against extinction by the pressure of the gas.

6. In a brazing burner, a body having a fuel chamber in one end and a pipe for conveying hydrocarbon gas thereto, a pipe on the opposite end of said body having a jet nozzle at its free end, a surrounding pipe also connected to the body concentric to the jet nozzle pipe and having a pilot burner at its free end adjacent to the jet burner, independent passage ways between each of said pipes and the fuel chamber, means for regulating the flow of gas through said passage ways, and a separate means mounted in the body for regulating the quantity of gas entering the jet nozzle pipe.

In testimony whereof I have hereunto set my hand in presence of two subscribing witnesses.

WILLIAM H. VAN HORN.
